UNITED STATES PATENT OFFICE

2,475,180

ELECTRIC HEATER

Raymond L. Fitch, West Los Angeles, Calif., assignor to The Firar Co., Santa Monica, Calif., a corporation of California

Application July 8, 1946, Serial No. 681,805

3 Claims. (Cl. 219—34)

1

My invention relates generally to space heaters and more particularly to electric heaters used to heat a room by both radiation and convection.

While the use of electric heaters employing resistance elements to heat a room is not new, previous heaters have generally relied on radiant heat alone and have made relatively small use of convection currents. In addition, portable heaters of this type have been of relatively light construction, mounted on small unstable bases which permitted them to fall or be knocked over very easily. If such a heater came to rest so that its beam was directed downwardly, the concentrated heat directed against the floor has been sufficient to cause serious damage to rugs and occasionally start dangerous fires. As a result, while such heaters have been effective in warming objects within their beams, they have been relatively inefficient in warming the room as a whole, and have been dangerous from the standpoint of a fire hazard where there has been a possibility of their being knocked over.

It is therefore a major object of my invention to provide an electric heater of simple but sturdy construction which rests firmly on a supporting surface without any tendency to fall.

Another object of my invention is to provide a heater which uses a resistance element to provide radiant heat, and is constructed to provide additional heat to the air in the room by means of convection currents.

A further object of my invention is to provide an electric heater which has a switch therein adapted to shut off power to the heater in the event it is tipped forward so as to concentrate a beam of heat onto the floor.

It is another object of my invention to provide a heater using commercially available resistance rods having a large radiating surface, used in conjunction with an improved reflector so that the housing containing the heater remains relatively cool.

These and other objects and advantages of my invention will become apparent from the following description of a preferred form thereof and from the drawings illustrating that form, in which:

Fig. 1 is a front elevational view of my improved heater;

Fig. 2 is a cross-sectional view taken at 2—2

2

in Fig. 1, showing the interior construction and arrangement of parts;

Fig. 3 is a vertical sectional view of the gravity responsive switch taken at 3—3 in Fig. 2;

Fig. 4 is a cross-sectional view of the switch taken at 4—4 in Fig. 3;

Fig. 5 is a horizontal sectional view of the lower portion of the heater taken at 5—5 in Fig. 1;

Fig. 6 is a horizontal sectional view of the heater taken at 6—6 in Fig. 1; and

Fig. 7 is a fragmentary vertical view taken at 7—7 in Fig. 5 showing the assembly of the lower and vertical reflector members.

Referring now to the drawings and particularly 15 to Fig. 1, the numeral 10 indicates generally a housing having an opening 11 in its forward surface which is covered by a grill 12. As seen in Figs. 5 and 6, the housing 10 includes a pair of vertically extending side members 13 and 14 20 which are formed as mirror images of each other, and consequently only one of the members will be described. The side member 13 is provided with an angularly positioned section 15 at its rear end which forms a portion of the rear wall of 25 the heater, and the innermost end of this section is provided with an inwardly extending "joggle" or offset portion 16 adapted to receive a back plate 17.

At its forward end, the side member 13 is bent 30 inwardly to provide an angularly positioned section 20, and from this section, another angle leads to a forward wall 21 which terminates in a re-entrant portion 22. The side member 13 thus extends completely across one side of the housing 10 and a short distance across the back thereof, while at its forward end it is, in effect, provided with a corner post construction which extends from the side portion of the member to the aperture 11. By making the side member 13 35 of relatively heavy gauge metal, a very strong construction is provided by the rear section 15 and the corner post construction at the forward edge. The side member 14, as previously mentioned, is formed as a mirror image of member 40 13, and the two members are joined together by a forward angle member 23 and a rear angle member 24, as shown in Fig. 6. The forward angle member 23 is substantially horizontal, and one of its ends is cut at an angle to abut against the angularly positioned section 20, with the

downwardly projecting leg of the angle, which is along the rear edge thereof, bent backwardly to attach to the side portions 13 and 14. The rear angle member 24 has its vertical leg abutting the rear section 15 of the side walls 13 and 14 and is suitably attached thereto as by spot welding; and the horizontal leg is bent downwardly to provide a surface bearing against the side members 13 and 14 to which it is likewise attached as by spot welding. The upper portion of the re-entrant section 22 of the side members 13 and 14 is cut away to receive the forward angle member 23, and the upper portion of the "joggle" section 16 is similarly cut away to receive the rear angle member 24.

Within the housing 10 and near the base thereof I provide a pan member 25 extending from side member 13 to side member 14, and from the rear portion 15 substantially to the forward surfaces 21 of the side members. The sides of the pan 25 abut the sides 13 and 14, and are provided with upwardly extending flanges 26, as shown in Fig. 7, which may be welded or otherwise securely fastened to the sides. The rear edge of the pan 25 is provided with an upwardly extending flange 27 which is spaced outwardly from the joggles 16, and extends between these joggles to hold the back plate 17 in a manner hereinafter described. At its forward edge, the pan 25 is bent upwardly and then rearwardly to form a channel-like section 28 which adds stiffness to the pan, and which acts to support various elements of the heater. The channel section 28 and the flange 27 are clearly indicated in Fig. 2 where there is also shown a bracket member 30 which may be welded or otherwise suitably attached to the rear portion of pan 25. The joggle 16 and the re-entrant section 22 of the side members 13 and 14 are cut away to receive the pan 25, in a manner similar to that mentioned in connection with angle members 23 and 24.

The back plate 17 consists of a flat plate fitting between the joggles 16 of the side members 13 and 14, and adapted to have its lower edge rest upon the pan 25 at the base of the upwardly extending flange 27. The upper edge of the back plate 17 is held in place by a top 31 which may be held to the housing 10 by means of screws which engage the forward and rearward angle members 23 and 24. It is thus seen that a very simple but ruggedly constructed housing has been provided to which access may be obtained by removing the cover 31 and then lifting off the back plate 17.

Within the housing 10 I provide a reflector assembly adapted to reflect the heat from the heating element outwardly through the opening 11. This reflector assembly includes a lower reflector 33, a vertical reflector 34, and an upper reflector 35. The lower reflector 33, shown in Fig. 5, includes a substantially flat horizontal portion 36 in the shape of a semi-circle with a groove 37 formed near its periphery and with a lip 38 extending generally forwardly and upwardly from the horizontal portion 36 to act as a guard in a manner hereinafter described. The forward edge of the horizontal portion 36 may be provided with a bead 40 as shown in Fig. 2 to provide a bearing surface which may rest on the upper surface of the channel portion 28 of the pan 25. The bead or groove 38 is adapted to rest on the forward end of bracket 30, and the overall distance between the sides of the horizontal portion 36 is such as to cause them to bear

against the re-entrant sections 22 of the side members 13 and 14 should the lower reflector 33 be urged forwardly.

The vertical reflector 34 consists of a sheet of polished metal, such as aluminum or copper, which is curved to provide a semi-circular cylindrical reflecting surface with its lower edge fitting into the groove 37 where it is held in the desired shape thereby. Along its forward edges, 5 the reflector 34 is provided with outwardly extending flanges 41 which are adapted to fit in flange receiving members 42 attached to or forming part of the re-entrant surfaces 22. The vertical reflector 34 is held against movement by the 10 groove 37 and the flange receiving members 42 so that it is firmly anchored in position, and aids in holding the lower reflector 33 in its desired position.

The upper reflector 35 is similar in most respects to the lower reflector 33 but consists solely of a horizontal portion having an upwardly extending flange 43 adapted to bear against the inner surface of the vertical edge of angle member 23. The reflector 35 is likewise provided with a 15 groove 44, shaped similarly to the groove 37 of the lower reflector 33, and this groove receives the upper edge of the vertical reflector 34 to aid in holding the latter in the desired shape, while being supported by it. To insure that the members 20 maintain their proper relationship, a spring member 45 is attached to the top 31 and bears against the upper surface of the reflector 35 to urge it, the vertical reflector 34, and the lower reflector 33 downwardly so that the latter bears 25 against the channel section 28 of the pan 25 and the bracket 30, thereby rigidly holding all members in proper alignment. While other materials 30 may be used for the reflectors 33, 34 and 35, I have found that polished aluminum is a very satisfactory material since it is a good reflector of 35 heat and is easily formed to the desired shape. If 40 desired, the vertical reflector 34 may be combined with one or both of the horizontal reflectors 33 and 35 by drawing or forming them in a metal 45 forming die.

I have found that resistance rods of carbide compounds or other suitable material are very satisfactory as heat producing elements, and 50 since these rods are readily available, I prefer to use one as my heating element, though other resistance elements may obviously be used. To support the rod, I mount a bushing type insulator 50 in the upper reflector 35 and provide a similar insulator 51 in the lower reflector 33. These insulators 50 and 51 are preferably located with respect to the vertical reflector 34 so that a heat beam of the desired characteristics will be emitted from the heater. I have found that by making the vertical reflector 34 in the shape of a semi-circular cylinder, and locating the heating element 55 so that it is parallel to the axis of the cylinder centrally spaced on a chord parallel to the reflector opening at a distance of $\frac{1}{17}$ of the radius from the center of curvature very satisfactory results are obtained. With a cylinder $4\frac{1}{4}$ inch radius, the center of the heater element is 2 inches 60 from the reflector; and a beam of heat is provided which is approximately 120° wide, as compared with a beam of approximately 45° with previous heaters.

The lower end of the conductor which extends 65 through the insulator 50 is connected to a spring member 52 which is preferably formed of a strip of metal such as phosphor-bronze or beryllium-copper bent in the shape of a U and plated with 70

cadmium, zinc, or other suitable metal to reduce electrolytic action. The upper arm of the U-shaped spring member 52 is attached to the connector extending through the bushing insulator 50, and the lower arm has a circular disc 53 of polished aluminum or other suitable material attached to it to act as a guard member. Concentric with the guard member 53 is a cup member 54 mounted on the lower side thereof, having a central recess adapted to receive one 10 end of a resistance rod 55. A similar assembly including a spring 56, a guard 57, and a cup member 58 is mounted on the connector extending through the lower bushing insulator 51, and the rod 55 is thus spring mounted in a vertical position within the cavity formed by the reflecting surfaces 33, 34, and 35.

The function of the guards 53 and 57 is to reflect heat radiated from the rod 55 away from the bushing insulators 50 and 51, and from the springs 52 and 56. In this way, the possibility of cracking of the insulators is greatly reduced and the resilience of the springs is maintained over an extended period of time. As a further aid in cooling the bushing 51 and to assist in establishing convection currents through the heater, a pair of louvered apertures 61 is formed in the lower reflector 33, and a hole or series of holes 62 is formed in the pan 25 as to permit air to enter the base of the heater and pass upwardly through the louvered opening 61 into the reflector cavity. Additional holes, not shown, are formed in the back plate 17 near the upper edge thereof to permit an additional flow of air through the heater to aid in cooling the latter and warming the air in the room.

Since the rod 55 is somewhat fragile, it is to be expected that the rod will sometimes break, and the pieces thereof might fall out of the heater. Should this breakage occur while the heater is in operation, the hot portions of the rod would constitute a serious fire hazard if they were permitted to fall onto the floor or rug on or near which the heater is resting. However, by providing the upwardly and forwardly extending lip 38 at the forward edge of the lower reflector 33, all such portions of the rod 55 will be caught and retained within the reflector cavity where they will do no harm. When the rod 55 is to be replaced, it is a simple matter to separate the cup members 54 and 58 a slight amount, remove the old rod, and insert a new one in its place. The spring members 52 and 56 insure that good electrical contact will be made to each end of the rod 55, and no special tools or experience are needed to effect the replacement.

In order to provide an exceptionally safe heater, I include within the housing 10 a gravity responsive switch 65 adapted to disconnect the resistance rod 55 from the power circuit should the heater be tipped forward an amount sufficient to direct most of the heat onto the floor where it might cause serious damage. As shown in Figs. 3 and 4, the switch 65 includes a weight 66 pendulously mounted on a shaft 67 and having an insulated operating arm 68 at the upper end thereof. The shaft 67 is journalled into a pair of brackets 70 which may be attached to the rear angle member 24, and a piece of insulating material 71 such as hard rubber, a phenolic resin, or other suitable material is attached to the brackets so that the insulator is parallel to the axis of the shaft 67. Mounted on the insulator 71 is a contact point 72 connected by a conductor 73 to a terminal 74. A cooperating contact point 75 is

mounted on a spring type conductor 76 which connects to a terminal 77, and the contacts 72 and 75 are arranged so that they are normally urged apart by the action of the spring conductor 76, but may be caused to bear against each other and complete a circuit from terminal 77 to terminal 74. When the pendulous weight 66 is in a vertical position and the housing 10 is in its normal upright position, operating arm 68 bears against the spring connector 76 to force contact 75 against contact 72 to complete the circuit as previously mentioned. However, should the heater be tipped forward so that the pendulous weight 66 moves with respect to housing 10 to assume the position shown in dotted outline in Fig. 4, the operating arm 68 will be moved away from contact 72, and contact point 75 will be separated from contact 72 by the urging of spring 76 to interrupt the circuit. It will be apparent, of course, that commercially available switches, such as snap-action limit switches, may be used in place of contacts 72 and 75, or a mercury switch may be used instead of the pendulous weight and switch combination herein disclosed.

The gravity responsive switch just described provides a convenient means for manually turning the heater off and on; and to do this, I prefer to use a pivoted member 80 which is adapted to move the pendulous weight to circuit breaking position. As shown in Figs. 3 and 4, the member 80 comprises a handle portion 81 which extends through a hole 82 in the back plate 17, and which has an operating arm 83 on its inner end. The operating arm 83 is so located that when the handle 81 is in its upper limiting position, shown in solid outline, the pendulous weight 66 is free to assume its usual positions; but when the handle is in its lower limiting position, shown in phantom outline, the pendulous weight is urged to circuit breaking position. An escutcheon plate 84 is mounted on the back plate 17, and has a hole 85 therein, aligned with hole 82, through which the handle 81 may extend. Preferably, the escutcheon plate 84 is provided with the legends "On" and "Off," corresponding to the conditions of the heater circuit with the handle adjacent the appropriate marking; and any other desired information may also be shown on the plate.

Laterally outward from the hole 82, the back plate 17 is depressed to form a pair of receiving grooves 86, shown in Fig. 4, which receive and hold a pair of ears 87 extending outwardly from handle 81. The ears 87 are formed so that they bear against the grooves 86 and the inner surface of the escutcheon plate 84, and the natural resilience of the latter provides an operation similar to an over-center spring, thereby urging the handle 81 to either its upper or its lower limiting position. The ears 87 also act to furnish pivotal support for the member 80, and thus a simple but sturdy construction is provided.

Connection to the resistance rod 55 may be made through a pin type connector plug 90 mounted on the bracket 30, with a conductor 91 leading from one terminal of the plug to the bushing type insulator 51. The other terminal of the plug is connected through a conductor 92 to terminal 77 of switch 65, from whence the circuit is completed by conductor 93 which connects terminal 74 to the conductor extending through the bushing type insulator 50. If desired, of course, the plug connector 90 may be omitted and the usual connecting cord supplied, having the customary plug on its end adapted to fit into the usual outlet socket. Connections are then

made in the same manner, with the exception that the plug connector 90 is eliminated.

To complete the heater, the grill 12 is mounted in front of aperture 11 by means of lugs on the horizontal portions of the grill which are fitted into holes (not shown) in the reentrant members 22 of the sides 13 and 14. By forcing the ends of the horizontal members of the grill 12 toward each other, they may be disengaged from their receiving holes and the entire grill pivoted to permit the easy replacement of the resistance rod 55.

It is thus seen that I have provided an improved heater which, while formed of relatively light material, makes use of the columnar strength of a formed sheet member to provide a very strong and rugged cabinet of great stability. Furthermore, the cabinet which I form from these members is readily assembled from simple, standard structural shapes with relatively few welded connections, and the remainder of the cabinet members and the reflector surfaces are held in position by the action of one member on another, the final holding being accomplished by the top which is secured in place by four screws. By removing these four screws, access may be secured to the entire interior of the cabinet, and by loosening the conductors therein, all portions of the reflector assembly and the heating element may be removed without further use of tools.

In addition to the strong and rigid assembly provided by my particular form of construction, the heater has safety features which have been lacking in previously available radiant heaters. The upwardly extending lip or baffle, formed as a continuation of the lower reflecting surface, prevents direct radiation of heat onto the floor near the heater and also acts to prevent glowing portions of the resistance rod from falling onto the floor should the rod break while the heater is in use. The provision of the safety switch prevents the operation of the heater when it is tipped forward, and thus there is no possibility of the heater being operated while it is lying face downward and capable of directing such a quantity of heat to the floor or rug as to burn the latter. The resistance element provides a beam of heat which is rich in infra-red radiation, and the construction of the heater is such that it promotes a circulation of air through and around the heater to cool the latter while the air itself is being warmed.

While I have shown and described a preferred form of my invention, it is obvious that changes may be made therein and I do not wish to be limited to the particular form or arrangement of parts herein described and shown, except as covered by my claims.

I claim:

1. A portable electric heater which includes: a pair of vertically extending side walls formed of sheet metal; cross members connecting said side walls together; a back plate adapted to be supported by one of said cross members; a top removably held to one of said cross members; a lower reflector supported by one of said cross members; a vertical reflector resting on said lower reflector; an upper reflector resting on said vertical reflector; resilient means extending between said top and said upper reflector to urge the latter against said vertical reflector, said vertical reflector against said lower reflector, and said lower reflector against said cross member to hold all said reflectors in alignment; and

means for mounting a resistance element in front of said vertical member.

2. A portable electric heater which includes: a pair of vertically extending sheet metal side walls having front and rear flanges forming columnar sections; a lower cross member connecting said side walls together; an upper cross member connecting said side walls together, said side walls being spaced apart, and said upper and lower cross members being vertically separated to form a housing having a front and a rear aperture therein; a top removably held to said upper cross member; a back plate adapted to be supported by said lower cross member to close said rear aperture, said back plate being engaged and held in place by said top; a lower reflector having a groove formed in its upper surface; said reflector being supported by said lower cross member; a vertical reflector adapted to fit within said groove in said lower reflector and be supported thereby, said vertical reflector being substantially aligned with said front aperture to reflect outwardly therefrom; an upper reflector having a groove formed in its lower surface to receive said vertical reflector; spring means attached to said top and bearing against said upper reflector to urge it, said vertical reflector, and said lower reflector downwardly, whereby said reflectors are securely held in position; a forwardly and upwardly projecting lip extending from the forward edge of said lower reflector; and resilient means adapted to support a resistance element within said housing between said vertical reflector and said front aperture.

3. A portable electric heater which includes: a pair of vertically extending sheet metal side walls having front and rear flanges forming columnar sections; a lower cross member connecting said side walls together; an upper cross member connecting said side walls together, said side walls being spaced apart, and said upper and lower cross members being vertically separated to form a housing having a front and a rear aperture therein; a top removably held to said upper cross member; a back plate adapted to be supported by said lower cross member to close said rear aperture, said back plate being engaged and held in place by said top; a lower reflector having a groove formed in its upper surface, said reflector being supported by said lower cross member; a vertical reflector adapted to fit within said groove in said lower reflector and be supported thereby, said vertical reflector being substantially aligned with said front aperture to reflect outwardly therefrom; an upper reflector having a groove formed in its lower surface to receive said vertical reflector; spring means attached to said top and bearing against said upper reflector to urge it, said vertical reflector, and said lower reflector downwardly, whereby said reflectors are securely held in position; a forwardly and upwardly projecting lip extending from the forward edge of said lower reflector; upper and lower terminal members adapted to receive the upper and lower ends respectively of a resistance element; upper and lower resilient members supporting said upper and lower terminal members respectively; upper and lower guard members of a heat reflecting material mounted between said terminal members and said resilient members to reduce the radiated heat reaching said resilient members; upper and lower insulators supporting said upper and lower resilient members respectively, said insulators being mounted in said upper and lower reflectors respectively to position said resistance

element within said housing between said vertical reflector and said central aperture; and switch means mounted in said housing adapted to control the circuit to said resistance element.
